UNITED STATES PATENT OFFICE

163,551

TRUNDLE TOY INSECT WITH ROTATABLE
WINGSFrederick E. Seyfarth, Evanston, Ill., assignor to
Fisher-Price Toys, Inc., East Aurora, N. Y.

Application December 13, 1949, Serial No. 6,591

Term of patent 14 years

(Cl. D34—15)

To all whom it may concern:

Be it known that I, Frederick E. Seyfarth, a citizen of the United States, residing at 2133 Ridge Avenue, Evanston, Illinois, in the county of Cook and State of Illinois, have invented a new, original, and ornamental Design for Trundle Toy Insect with Rotatable Wings, of which the following is a specification, reference being had to the accompanying drawing, forming part thereof.

Fig. 1 is a top perspective view of the trundle toy insect with rotatable wings, showing my new design;

Fig. 2 is a side elevational view thereof;

Fig. 3 is a top plan view thereof; and

Fig. 4 is a front end elevational view thereof.

I claim:

The ornamental design for a trundle toy insect with rotatable wings, as shown.

FREDERICK E. SEYFARTH.
